APPLIANCE PORTABLE LIFTER

Larry M. Lantz, 563 Harrison, Pawnee, Okla. 74058,
and William L. Mitchell, 321 7th St., Perry, Okla.
73077

Filed Apr. 26, 1974, Ser. No. 464,528

Term of patent 14 years

Int. Cl. D12—05

U.S. Cl. D12—56

Fig. 1

Fig. 2

Fig. 3

Fig. 4

Fig. 5

Fig. 6

FIG. 1 is a front elevational view of an appliance portable lifter showing our design;

FIG. 2 is a side elevational view thereof;

FIG. 3 is a bottom plan view thereof;

FIG. 4 is a top plan view thereof;

FIG. 5 is a rear elevational view thereof;

FIG. 6 is a side elevational view thereof opposite to that shown in FIG. 2.

We claim:

The ornamental design for an appliance portable lifter, substantially as shown.
